STOP AND TURN SIGNAL FOR AUTOMOBILES

Filed Oct. 9, 1924

FIG. 1.

Inventor
Henry Masbruch

By *Lester L. Sargent*
Attorney

UNITED STATES PATENT OFFICE.

HENRY MASBRUCH, OF PLATTEVILLE, WISCONSIN.

STOP AND TURN SIGNAL FOR AUTOMOBILES.

Application filed October 9, 1924. Serial No. 742,567.

To all whom it may concern:

Be it known that I, HENRY MASBRUCH, a citizen of the United States, residing at Platteville, in the county of Grant and State 5 of Wisconsin, have invented a new and useful Stop and Turn Signal for Automobiles, of which the following is a specification.

The object of my invention is to provide an improved manually operated stop and 10 turn signal for automobiles; to provide a device which is completely under the control of the operator; and to provide a device which, although of relatively simple mechanism, will function efficiently. I at- 15 tain these and other objects of my invention by the device illustrated in the accompanying drawings, in which—

Figure 1 is an edge elevational view of the device applied to an automobile;

20 Fig. 2 is a portion of the same view enlarged; and

Fig. 3 is a vertical section on line 3—3 of Fig. 2.

Like characters of reference indicate like 25 parts in each of the several views.

Referring to the accompanying drawings, I provide suitable casing members 1 and 2 within which is swingably mounted a hand 3 loosely mounted on the pivot pin 4. At- 30 tached to the shank 5 of the hand is a wire or cable 6 which is attached at 8 to the lever 7 which lever is swingably mounted on the pivot 9, as shown in Fig. 3. Lever 7 is operated by a suitable wire or cable 10 35 which is extended over rollers 11 and is provided with a button or ring 13 attached to the end 12 of the wire or cable, as shown in Fig. 1. I further provide a suitable spring 14 attached at 16 to one of the cas- 40 ing members 1 or 2 and at the other end to the hand 3 approximately at the point 15, as shown in Fig. 3. This spring 14 functions to normally hold the hand in a concealed position within the casing mem- 45 bers 1 and 2. In operating this device the button or ring 13, which is preferably po- sitioned just below the steering wheel, is pulled thus causing hand 3 to swing to a

horizontal position to indicate that the driver of the car is about to make a turn. 50 By quickly pulling and partially releasing the cable the hand may be caused to wave back and forth to indicate that the driver is about to slow up or stop the car.

What I claim is:

1. In a turn and stop signal for automo- 55 biles, the combination of spaced casing mem- bers, a pin extending between said casing members, a hand depending from and swingably mounted on said pin, the hand 60 being suitably positioned relative to the casing to permit of its being swung to either an exposed horizontal position, slanting po- 65 sition or concealed vertical position accord- ing to the direction in which the vehicle 70 is to turn, a lever pivotally mounted on the casing members, a wire cable attached to the shank of the hand and near the other end of the lever, and a second wire or cable attached to the extreme outer end of the 75 lever and having a member adapted to be grasped by the operator attached to the free end of the wire or cable, and rollers over which the wire or cable is threaded.

2. In a turn and stop signal for automo- 75 biles, the combination of means for encas- 80 ing a signal element, a swingable signal ele- ment pivotally mounted in said casing means and normally concealed therein, the swing- 85 able element being suitably positioned rela- tive to the casing to permit of its being 90 swung either to an exposed horizontal po- sition, a slanting position, or a concealed ver- tical position, resilient means operatively connected to the signal element and to the casing means and adapted to draw the sig- 95 nal element to a concealed position, means operatively connected with the shank of the signal element for swinging same to a dis- play position, and a wire or cable connected to the last-mentioned means and extending to an operative position within easy reach of the steering wheel, substantially as de- 100 scribed.

HENRY MASBRUCH,
